UNITED STATES PATENT OFFICE.

EDWARD D. WELLS, OF WESTMINSTER, MARYLAND.

ELECTRIC RAILWAY-SIGNAL.

SPECIFICATION forming part of Letters Patent No. 357,881, dated February 15, 1887.
Application filed November 20, 1886. Serial No. 219,520. (No model.)

To all whom it may concern:

Be it known that I, EDWARD D. WELLS, of Westminster, in the county of Carroll and State of Maryland, have invented a new and 5 useful Improvement in Electric Railway-Signals, of which the following is a specification.

The object of my invention is to prevent accidents from trains running into each other, or from trains running into vehicles at crossings.

My invention contemplates the division of a line of railroad into sections, after the manner of the block system, and providing electrical connections and signals for each section 15 whereby one train is automatically signaled and prevented from entering one section of track until the train on that section has passed off of the same.

My invention consists in the peculiar construction and arrangement of the circuit, contacts, and signaling mechanism, whereby the above object is accomplished, and which construction is equally applicable as a switch-signal. This construction I will now proceed 25 to describe with reference to the accompanying drawings, in which—

Figure 1 is a perspective view of a track with the signaling devices applied for trains moving in one direction. Fig. 2 is a diagrammatic view showing the arrangement of the 30 circuits and their connections to the battery and signaling apparatus. Fig. 3 shows the means for giving a signal on a bell of a train, indicating that the preceding train has not 35 passed off the section of track that is being entered upon by the second train; and Fig. 4 is a view showing my invention applied as a switch-signal.

I employ for each section of track three sets 40 of electrical contacts, A A, B B, and C C, in connection with a visible signal, D E F, and an alarm-bell on each train. The contacts B B are at the beginning of each section of track, and serve to set the danger-signal for that 45 section. The contacts C C are at the end of each section of track, and serve to remove the danger-signal for that section, and the contacts A A are a little in advance of B B, and serve by the automatic setting of the danger-signal 50 to sound an alarm on an electric bell of the train in rear and give a preliminary warning before the engineer comes in sight of the visi-

ble signal D E F. The contacts A A are insulated from each other, and are never directly connected, but are terminal electrodes that 55 transmit a current through sliding conductors A² A² (see Fig. 3) on the locomotive or car, which conductors connect with the magnets of an alarm-bell, A³.

The contacts B B are spring-contacts and 60 normally open, but are forced together by contact with some part of the train to close a current through one set of magnets that present the danger-signal. The contacts C C are of a similar character, and are forced together by 65 contact with some part of the train to close a current through another set of magnets, and throw off the danger-signal from that section of track.

Referring now to Fig. 2, I will describe 70 the peculiar arrangement of the circuits and their method of operation in connection with the signaling devices. The letters A A indicate the bell-contact A A of Fig. 1; the letters B B, the signal-setting contacts B B of Fig. 1, 75 and the letters C C the signal-removing contacts C C of Fig. 1. The letters a a, b b, and c c represent the several circuit-wires of these contacts, which wires connect with the battery X, as shown, and extend up the mast D 80 of Fig. 1, and connect with magnets in the case E, which operate the signal-arm F of the danger-signal.

The connections are made as follows: The 85 circuit-wires a a of the bell-contacts A A connect through the battery with the terminal contact-springs a² a², which are normally separated from each other. The circuit-wires b b of the signal-setting contacts B B connect through the battery with the magnet G, and 90 the circuit-wires c c of the signal-removing contacts C C connect through the battery with the magnet H. These two magnets G and H act upon opposite sides of a segment-wheel, I, 95 as an armature, one pulling the segment-wheel in one direction and the other in the reverse. This segment-wheel engages with its teeth a small gear-wheel, J, on the same shaft that bears the signal-arm F. On this same shaft 100 also there is an arm, K, which, when the signal-arm is set horizontally to indicate "danger," bears against one of the springs a² and forces it into contact with the other.

The operation of my invention is as follows:

As shown, the danger-signal has just been set by a closure of the contacts B B, which has thrown the battery-current through magnet G, and which, acting upon the segment-armature, has rotated the signal-arm into a horizontal position indicating "danger," and which same motion has by arm K closed the spring-contacts $a^2 a^2$. This condition of things is preserved as long as a train is in this section, and 10 if another train should approach before the first train has left said section, as soon as the conductors A² A² (see Fig. 3) of this second train strike the contacts A A the battery-current from the wires $a a$ passes up and through the bell A³ on this approaching train, and by sounding an alarm calls the attention of the engineer to this fact, who afterward has this signal confirmed by the visible signal on the mast. As soon as the train passes off this 15 section of track the contacts C C are brought together by the train passing, and the battery-current passing through magnet H throws the segment-armature in the opposite direction, restoring the signal-arm to its vertical position, and thus removing the danger-signal. The same motion also throws the arm K away from springs a^2 and allows the two springs to 20 separate, so that even if the conductors A² A² of a coming train strike the contacts A A no signal is given in the bell of the train, for the reason that the battery-circuit $a a$ is open at 25 $a^2 a^2$.

In locating the contacts A A B B C C they may be placed either in the track-bed or in 30 any other position to be operated by the passing trains.

In Fig. 4 I show a modification of my invention as applied to switch-signaling. The contacts B B and C C of Fig. 1 are merely carried to and controlled by the position of the 40 switch-rail through a rod and sliding plate, S. When S closes contacts C C, the main line is continuous, and there is no danger-signal displayed. When main line is open, slide S closes contacts B B and the danger-signals are given 45 just as described with reference to diagram Fig. 2.

Having thus described my invention, what I claim as new is—

1. The combination, with a battery, a signal-arm, a signal-bell, and conductors A² A² on the car, of the contacts A A, for connection with the bell-conductors, the contacts B B and means for setting the signal, and the contacts C C and means for removing the signal, substantially as and for the purpose described. 55

2. The combination of magnets G H, segmental armature I, shaft with pinion J, signal-arm F, and arm K, the contacts A A, with circuit $a a$ and terminals $a^2 a^2$, arranged to be 60 closed by arm K, signal-displaying contacts B B, electrically connected with magnet G, and signal-removing contacts C C, electrically connected with magnet H, substantially as and for the purpose described.

EDWARD D. WELLS.
